UNITED STATES PATENT OFFICE.

SAMUEL R. LEYSON, OF NASHUA, NEW HAMPSHIRE.

IMPROVEMENT IN METAL-BENDING MACHINES.

Specification forming part of Letters Patent No. 146,538, dated January 20, 1874; application filed November 26, 1873.

To all whom it may concern:

Be it known that I, SAMUEL R. LEYSON, of Nashua, in the county of Hillsborough, of the State of New Hampshire, have invented an Improved Machine for use in Bending Metal; and do hereby declare the same to be fully described in the following specification, and represented in the accompanying drawings, of which—

Figure 1 is a top view, Fig. 2 a side elevation, Figs. 3 and 4 longitudinal sections, and Fig. 5 a transverse section, of it.

The machine or invention consists in an adjustable yoke, its operative screw, a main bed or anvil, an angular abutment, and an auxiliary bed, provided with a curved and slotted arm and a clamp-screw and nut, all being substantially as hereinafter described, and as represented in the aforesaid drawings.

In such drawings, A denotes a stationary metallic bed or anvil, mounted upon a stand, B. The said bed or anvil has a square or rectangular shape, and is rabbeted or recessed, as shown at a, the recess being exhibited more particularly in Fig. 6, which is a top view, and Fig. 7, which is a side elevation of the said bed. At its front end the recess terminates against an angular abutment, arranged as shown. The recess receives an auxiliary or adjustable bed, D, whose front end is beveled, as shown, to rest against the inner face of the abutment. From the adjustable bed a circularly-curved arm, E, furnished with a concentric slot, b, projects, such arm being carried through a slot, c, in the main bed. A clamp-screw, F, furnished with a nut, G, and arranged with the arm E and the stand B, in manner as shown, serves, with the arm, to hold the auxiliary bed in any desirable inclination or obtuse angle with the front face of the abutment. The said front face with the rest of the front face or edge of the bed A, stands at a right angle with the upper surface of the bed. A rectangular frame or yoke, H, arranged about the main and auxiliary beds, and supported on the main bed in the manner as rep-

resented, is provided with a screw, I, for moving it longitudinally. The screw I screws into and through the yoke, is pivoted to the main bed, and provided with a handle or slide-lever, K, all being arranged as represented.

With the said machine a bar of metal may be bent at a right angle or an obtuse angle.

Preparatory to bending the bar at a right angle, such bar, to the depth required or to the place of bending, is to be inserted downward between the yoke and the front edge of the anvil, and the yoke, by means of its adjusting-screw, should be drawn back upon the bar, so as, with the bed, to hold it firmly, after which the bar is to be bent down upon this and into close contact with the upper surface of the bed.

To bend the bar at an obtuse angle, the auxiliary bed should first be raised so that its upper surface may make the requisite angle with the front face of the abutment, after which the clamp-nut should be set up, so as to confine the bed in its raised position. The bar to be bent is next to be inserted between the yoke and the said face of the abutment, and the yoke should be drawn up to the bar, so as to clamp it to the abutment. Finally, the bar should be bent down upon, and so as to conform to the upper surface of the auxiliary bed.

The machine will be found to be of great advantage to a blacksmith or a carpenter, especially in bending metallic plates or bars for brackets or braces.

I claim—

The machine, substantially as described, composed of the adjustable yoke H, its operative screw I, the main bed or anvil A, and its abutment C, and the auxiliary bed D, provided with the curved arm E and the clamp-screw F and nut G, all being combined and arranged in manner and to operate essentially as specified and represented.

SAMUEL R. LEYSON.
